UNITED STATES PATENT OFFICE.

CHARLES E. GLASSPOOLE, OF ST. PAUL, MINNESOTA.

CULVERT.

No. 901,703.

Specification of Letters Patent.

Patented Oct. 20, 1908.

Application filed March 3, 1908. Serial No. 418,941.

To all whom it may concern:

Be it known that I, CHARLES E. GLASSPOOLE, a citizen of the United States, residing at St. Paul, in the county of Ramsey and State of Minnesota, have invented a new and useful Improvement in Culverts, of which the following is a specification.

My invention relates to an improved culvert and more particularly is a modification of the construction set forth in my application for patent Serial No. 410,560, filed January 13, 1908.

The primary object in this invention as in the invention set forth in said application is simple and inexpensive construction together with greater effectiveness in use.

This invention has to do with that class of culverts which is reinforced in strength by its particular construction and which is adapted to completely drain water therefrom. Prior to the use of my invention it has been customary when constructing culverts out of sheet metal to use circumferentially corrugated pipe, the corrugations passing completely around its surface and the interstices between said corrugations retaining a certain amount of the drainage which tends to attack and rust the metal. My invention completely overcomes this objection in a simple and effective manner and at the same time increases the strength and minimizes the cost of construction and reduces the wear and friction against water drained by the culvert. By reducing the friction, the capacity of the culvert is very much increased. It will be noted that in culverts employing circumferential corrugations a whirling effect is imparted to the water passing through it, while my invention allows the water to pass freely through without whirling.

In the accompanying drawings, forming part of this specification: Figure 1 is a longitudinal section showing the ends of detail portions of two lengths of my improved culvert joined together: Fig. 2 is a side view showing detail portions of two lengths of my improved culvert separated and in readiness to be joined together: Fig. 3 is a cross sectional view of a modified construction, the line of section being indicated by X—X shown in Fig. 1; Fig. 4 is a plan of a detail portion of a sheet of material corrugated and in readiness to have its side edges turned and secured together to form a part of a length of

culvert; Fig. 5 is a longitudinal section of culvert showing a modified construction, and Fig. 6 is a transverse section taken on the line Y—Y of Fig. 5.

In the drawings A represents a section of culvert having my invention which is in the form of a pipe the ends of lengths 2 and 3 of which are joined together in the following manner to form a complete line of culvert. The section of culvert as shown is provided with upper and lower longitudinal parts which are respectively corrugated at 4 and smooth at 5 the corrugations of the former running transversely and in cross section appearing in the form of reverse curves, or of any other suitable form or shape desired for the purpose of reinforcing the strength of the thin sheet metal or other material out of which the culvert is preferably made.

The upper and lower parts of the culvert are integral being made out of a single sheet of material. The sides of the sheet are connected by a lap joint B. the parts of which are secured together by means of rivets 6. welding or both as desired. The lower part of the culvert has a smooth inner surface and is not provided with corrugations, so that when the culvert is in use all of the water in it flows out and is not held by the interstices between corrugations as when the latter entirely encircle the culvert.

The corrugations may be varied in length to nearly circumscribe the culvert when desired but never entirely encircle the culvert within the scope of my invention. The method of joining the lengths at C as shown consists of securing one end of the length 2 over the adjoining end of length 3. After these parts are connected in the manner described the rivets are secured in place to complete the joint B.

In the modified construction shown in Fig. 3 the lower or smooth portion of the ends of the culvert at the joint C are secured together by rivets 6 for the purpose of increasing the strength of the joint and it is obvious that this method of securing the parts together may be varied as desired.

In forming the sheet to make the culvert out of a single piece of material, the corrugations are pressed into the sheet while lying flat and before it is bent into cylindrical shape and in order to prevent distorting the plane of the material the sheet is held firmly in place by jaws or other suitable means so

that the dies or forming tools produce the corrugations by stretching the metal into shape.

While this culvert is shown of substantially hollow cylindrical shape yet it is obvious that it may be made of any suitable cross sectional design as desired and that the corrugated part may extend a greater or less distance up or down at the sides of the culvert.

10 It is also obvious that the culvert may be curved or otherwise shaped longitudinally when desired and while described as being made out of metal it may be made successfully out of other suitable material.

15 In Fig. 5, a longitudinal corrugation 7 is formed in each side of the culvert for the purpose of allowing expansion and contraction of the material. Such longitudinal corrugations it will be noticed do not tend to obstruct the passage or hold any water in interstices as with transverse corrugations. In this construction the culvert is formed with a brazed joint at its side in accordance with the above description.

20 25 In accordance with the patent statutes I have described the principle of operation of my invention together with the construction which I now consider to represent the best embodiment thereof, but I desire to have it understood that the construction shown is only illustrative and that the invention can be carried out by other means and applied to uses other than those above set forth, within the scope of the following claims.

30 35 Having described my invention, what I claim as new and desire to protect by Letters Patent, is:

1. A device of the class set forth, comprising a pipe having longitudinal upper and lower integral parts, said upper part having transverse corrugations and said lower part an inner smooth surface, for the purposes specified.

2. A culvert of the class set forth, comprising, a sheet metal pipe having upper and lower integral parts, said upper part being intersticed to reinforce the strength of the culvert and said lower part having a smooth inner surface, for the purposes specified.

3. A culvert of the class set forth, comprising, a pipe made out of a thin sheet and having upper and lower parts, said upper part having a series of transverse corrugations and said lower part a longitudinal smooth in-

ner surface, the side edges of said sheet being secured together and forming a longitudinal joint, for the purposes specified.

4. A culvert in the form of a pipe made out of a single piece of sheet metal having a reinforced upper longitudinal part provided with transverse corrugations and a lower part having a longitudinally smooth inner surface, for the purposes specified.

5. A culvert of the class set forth, comprising, two lengths the ends of which being joined together, each of said lengths comprising a pipe having upper and lower integral parts, the upper part having a series of transverse corrugations and the lower part a longitudinal smooth inner surface, for the purposes specified.

6. A culvert of the class set forth, comprising a single piece of sheet material having a longitudinal series of transverse corrugations at one side and a longitudinal smooth surface adjoining said corrugations, the side edges of said sheet being joined together, for the purposes specified.

7. A culvert in the form of a pipe made out of thin material having a reinforced upper longitudinal part and a lower longitudinal part having a smooth inner surface and a joint securing the parts of said sheet together.

8. A culvert in the form of a pipe made out of a single sheet of material having a reinforced upper longitudinal part and a lower part having a smooth inner surface, one of said parts having a longitudinal corrugation.

9. A culvert comprising a surrounding integral wall having a transversely corrugated upper surface, and a smooth longitudinal lower surface for the purposes specified.

10. A device of the class set forth, comprising, a culvert in the form of a pipe made out of a single piece of sheet metal and having upper and lower parts 4 and 5, said upper part having series of transverse corrugations 4 and said lower part a longitudinally smooth inner surface 5, said parts being joined together longitudinally at one side of the pipe, for the purposes specified.

In testimony whereof, I have signed my name to this specification, in the presence of two subscribing witnesses.

CHARLES E. GLASSPOOLE.
